UNITED STATES PATENT OFFICE.

JOHN M. RUSBY AND JOHN HAWLEY TAUSSIG, OF PHILADELPHIA, PENNSYLVANIA,
ASSIGNORS TO THE UNITED GAS IMPROVEMENT COMPANY, OF PHILADELPHIA,
PENNSYLVANIA, A CORPORATION OF PENNSYLVANIA.

PROCESS OF REGULATING THE TEMPERATURE OF COMBUSTION.

1,110,991.

Specification of Letters Patent. Patented Sept. 15, 1914.

Application filed December 27, 1909. Serial No. 535,178.

To all whom it may concern:

Be it known that we, JOHN M. RUSBY and JOHN HAWLEY TAUSSIG, both citizens of the United States, and residents of Philadelphia, in the county of Philadelphia and State of Pennsylvania, have jointly invented a certain new and useful Process of Regulating the Temperature of Combustion, of which the following is a specification.

10 The principal objects of the present invention is to provide an improved process for the application of gaseous products of combustion to the control of the temperature of the products of combustion.

15 The process will be claimed at the end hereof, but will first be described in connection with the accompanying drawings which show two of the many forms of apparatus in connection with which the invention may 20 be practised.

In the drawings, Figure 1, is a side view, partly in section, of a coal gas retort bench in connection with which the process of our invention can be practised. Fig. 2, is a 25 transverse sectional view of the same, and Fig. 3, is a view, partly in longitudinal section, illustrating a modified construction of coal gas retort apparatus in connection with which the invention can be practised.

30 Referring to Fig. 2, a supply of combustible gas is maintained within the chamber 1, as shown, by generating it in that chamber and the path of travel of this gas is from chamber 1 through the passage 2 to the retort chamber 3. In the passage 2 the 35 gas is ignited by the addition of secondary air and products of combustion are thereafter added to it so as to control the temperature effect, all as will be described. The 40 flues 4 of the recuperator receive the products of combustion from the chamber 3 and they range from front to back of the setting alternately and downward and connect with the stack 5. Secondary air entering 45 for example at *s* traverses the flues 6 of the recuperator and is introduced into

the passage 2, causing ignition of the gas which is generated in the chamber 1 and permitting of its subsequent combustion in the retort chamber 3. Some of the products 50 of combustion which would ordinarily pass to the stack are introduced as a diluent in the passage 2. This is accomplished by the passage 8 that leads to the flues 4 and to a specially provided flue 9 that runs lengthwise and in the direction of the flues 4 and has communication by openings 10 with the passage 2, beyond the zone or region of ignition. In the flue 9, an injector 11 is shown which serves to insure the passage of 55 products of combustion from the flue 4 through the passage 8 to the passage or flue 9 and hence by the openings 10 to the passage 2. This injector may be operated by steam or by air, or by any appropriate 60 means. As a matter of fact the injector is merely illustrative of some appliance for introducing products of combustion. *t* are flues which by the ports *t*¹ deliver air into the chamber 1 for use in generating gas 70 from suitable fuel arranged in the chamber 1.

In Fig. 3, the fluid combustible is generated in a producer 12, which constitutes a separate piece of apparatus from the retort 75 bench and may be common to a number of retort benches. In this construction gas from the producer 12 enters the chamber 1^a, instead of being generated in that chamber, otherwise the construction and mode of 80 operation is the same as has been described in connection with Figs. 1 and 2; that is to say, the gas rises from the chamber 1^a into the passage 2^a. In the passage 2^a products of combustion are discharged from the openings 10^a and secondary air is admitted from 85 the openings 6^a.

The retorts 7 are arranged in the chamber 3 and by reason of the described control of the temperature of combustion they are 90 evenly heated; that is to say, those at the bottom are not unduly heated.

What we claim is:

The process of regulating the temperature effect of combustion which consists in burning a mixture of undiluted air and undiluted homogeneous producer gas, and adding to the burning products thereof a diluent consisting of incombustible products of combustion.

In testimony whereof we have hereunto signed our names.

JOHN M. RUSBY.

JOHN HAWLEY TAUSSIG.
